UNITED STATES PATENT OFFICE.

FRANCIS J. LINGG, OF PHILADELPHIA, PENNSYLVANIA.

DESIGN FOR A FINGER-RING.

SPECIFICATION forming part of Design No. 25,910, dated August 11, 1896.

Application filed April 27, 1896. Serial No. 589,326. Term of patent 7 years.

To all whom it may concern:

Be it known that I, FRANCIS J. LINGG, a citizen of the United States, and a resident of the city of Philadelphia, State of Pennsylvania, have invented a certain new Design for Finger-Rings, of which the following is a full, clear, and exact description, reference being had to the accompanying drawing, forming part of the specification.

10 My design for a finger-ring is shown in the annexed drawing, which represents the ring in perspective.

The leading feature of my design consists in the series of varicolored parallel circles of 15 about equal width on the periphery of said ring.

Referring to the drawing, A represents the finger-ring, on the periphery of which are colored circles or rings *a b c*, which are preferably red, white, and blue, respectively. The 20 various colored rings are interrupted to form an open space *d*, on which suitable letters or design may be placed.

What I claim is—

The design for a finger-ring substantially as 25 herein shown and described.

In witness whereof I have hereunto set my hand this 31st day of March, A. D. 1896.

FRANCIS J. LINGG.
